DESIGN FOR A RACK FOR A REFRIGERATOR, OVEN, OR THE LIKE

Leonard A. Young, Detroit, Mich.

Application September 19, 1940, Serial No. 95,199

Term of patent 14 years

To all whom it may concern:

Be it known that I, Leonard A. Young, a citizen of the United States, residing at Detroit, in the county of Wayne and State of Michigan, have invented a new, original, and ornamental Design for a Rack for a Refrigerator, Oven, or the like, of which the following is a specification, reference being had to the accompanying drawing, forming part thereof, in which:

Fig. 1 is a top plan view of a rack, for a refrigerator, oven or the like, showing my new design.

Fig. 2 is an end elevational view;

Fig. 3 is a front elevational view; and

Fig. 4 is a sectional view, shown on a large scale and partially broken away, taken along the line 4—4 of Fig. 1.

I claim:

The ornamental design for a rack for a refrigerator, oven, or the like, as shown.

LEONARD A. YOUNG.
